UNITED STATES PATENT OFFICE.

JOSEPH T. SHELHORN, OF ST. PAUL, INDIANA.

VENDING-MACHINE.

1,194,557.

Specification of Letters Patent. Patented Aug. 15, 1916.

Application filed March 4, 1916. Serial No. 82,148.

To all whom it may concern:

Be it known that I, JOSEPH T. SHELHORN, a citizen of the United States, residing at St. Paul, in the county of Decatur and State of Indiana, have invented certain new and useful Improvements in Vending-Machines, of which the following is a specification.

This invention relates to an improved vending machine of the coin control type and the principal object of the invention is to provide a machine having improved article holding mechanism and improved coin control mechanism for releasably preventing movement of the article holding mechanism and to further so construct the coin control mechanism that it may be regulated according to the size of the coin to be used and also so construct this mechanism that when the article holding mechanism has been emptied, the coin control mechanism may not be operated.

Another object of the invention is to so construct this coin control mechanism that only certain coins may be used and a larger coin prevented from entering and a smaller coin permitted to enter but prevented from actuating the coin control mechanism.

Another object of the invention is to so construct this machine that it will be comparatively small and compact in structure thus taking up a small amount of room but permitting a comparatively large amount of merchandise to be dispensed.

Another object of the invention is to so mount the coin box that it may be easily removed when desired.

Another object of this invention is to provide improved means for holding the vending machine in an assembled position.

Another object of the invention is to provide an improved closure or front wall for the machine, the closure being provided with a flange serving as a closure for the outlet opening and the actuating handle for this closure or front wall serving as a counterweight to return the closure to the set position after the machine has been operated.

Another object of the invention is to so construct this machine that springs or other means are not necessary for returning the various parts to their normal positions with the exception of a spring for holding one of the coin gripping jaws in a normal position

and a second spring for yieldably holding a pawl in a set position.

Another object of the invention is to provide a coin control vending machine which will be simple in operation, strong and durable in construction and not liable to easily get out of order or need repair.

This improved coin control machine is illustrated in the accompanying drawings, wherein:

Figure 1 is a view showing the machine in front elevation. Fig. 2 is a view in elevation looking at the inner face of the front wall or closure. Fig. 3 is a vertical sectional view through the machine. Fig. 4 is a sectional view taken along the line 4—4 of Fig. 3. Fig. 5 is a view taken along the line 5—5 of Fig. 3, to disclose the manner of releasably mounting the coin box. Fig. 6 is an enlarged sectional view taken along the line 6—6 of Fig. 3. Fig. 7 is a perspective view of the band which together with its external arms forms the merchandise compartment. Fig. 8 is a perspective view of the abutment plates limiting the rotary movement of the closure in one direction. Fig. 9 is a view showing the pawl in the lower portion of Fig. 3 in top plan. Fig. 10 is a perspective view of the bracket for the pawl shown in Fig. 9. Fig. 11 is a perspective view of the pawl shown in Fig. 9. Fig. 12 is a perspective view of a plate forming the coin control mechanism shown in Fig. 3. Fig. 13 is a view of brackets forming part of the coin control mechanism. Fig. 14 is a perspective view of the adjustable coin engaging jaw. Fig. 15 is a perspective view of the latch and movable coin engaging jaw shown in Fig. 3. Fig. 16 is a sectional view through the lock shown in Fig. 2. Fig. 17 is a perspective view of the leaf spring forming part of the lock.

The body portion or housing 20 of this dispensing machine is circular and has its walls 21 cut away at one point as shown in Fig. 3 thus producing an outlet 22 through which the merchandise may pass out of the machine. The closure or cover 23 is rotatably mounted upon this housing and has its wall 24 provided with a cutout 25 which registers with the outlet opening 22 when the closure is moved to the position indicated by dotted lines in Fig. 1 thus permitting

the merchandise to pass out of the machine. This closure is provided with an actuating handle 26 which is connected with the wall of the closure by means of rivets or other fasteners 27 and engaging the abutment strip 28 when in the position shown in Figs. 1 and 3 thus limiting the rotary movement of the closure in one direction. The housing 20 carries a sleeve 29 which fits upon the screw 30, the sleeve being provided with a flange 31 for engagement by the locking disk 32. This locking disk 32 is rotatably connected with the closure by means of the socket piece 33 and when in the locked position 15 extends across the flange 31 thus preventing removal of the cover. A latch 34 is secured as shown in Fig. 16 and extends across the socket with its free end terminating in a tooth 35 which fits into the notch 20 36 to releasably prevent rotation of the locking disk. When it is desired to remove this closure, the key 37 is inserted as shown in Fig. 16 and moves the latch 34 to the inoperative position thus permitting the locking disk to be rotated to an inoperative position 25 when desired.

In the housing or body portion there is positioned a band 38 having arms 39 extending therefrom to provide partitions and 30 being further provided with internal ribs 40 forming abutments. These abutments 40 will be engaged by the pawl 41 when the closure is rotated by swinging the handle 26 upwardly and the band 38 will be rotated 35 within the housing. This pawl 41 which is shown in Fig. 11 is pivotally mounted upon the longer arm 42 of the bracket 43 and will be yieldably held in the position shown in Fig. 3 by means of the spring 44, one arm 40 45 of which engages the pawl and the second arm 46 of which engages the shorter arm 47 of the bracket as clearly shown in Fig. 9. Upon return of the closure to the normal position, the pawl will ride over the 45 abutments 40 thus preventing the band 38 from being rotated when the closure is returning to the normal position to close the outlet opening 22.

A bracket 48 is secured to the housing and 50 provided with teeth 49 forming a clutch which are engaged by the teeth formed upon the foot 50 of the adjustable jaw 51. A set screw 52 passes through slot 53 in the foot of this adjustable jaw 51 and into the 55 threaded opening 54 of the bracket 48. The adjustable jaw can therefore be easily moved into the desired position and releasably held therein. A plate 55 is secured to this bracket 48 and carries a pin 56 which is adjustably 60 mounted so that it may be moved to the proper position according to the size of the coin to be used for operating the machine. Movable jaw 57 is pivotally connected with the bracket 43 by means of pivot pin 58 and 65 is provided with an extension forming a latching pawl 59 for engaging the abutments 40 of the band 38. This pawl is releasably held in engagement with one of the abutments 40 by means of the spring 60 which is wound upon the pivot pin 58 and 70 has one arm 61 engaging the pawl 59 and the second arm 62 engaging the bracket. The insertion of a coin to the position indicated by dotted lines in Fig. 4 moves the movable jaw and in so doing swings the latching pawl 59 out of a position for engagement with the abutment. Therefore this device cannot operate unless a coin is inserted and further it cannot operate unless the proper size coin is used. When in place the coin 80 is positioned as indicated by the dotted lines and from an inspection of Fig. 4, it will be readily seen that the coin will be placed in the path of movement of the lug 63 carried by the cover or closure 23. When this 85 closure is moved to bring the outlet 25 into registry with the outlet 22, the lug 63 will strike the coin thus moving it out of position between the jaws and permitting the pawl 59 to return to the operative position 90 shown in Fig. 3. The coin drops into the coin receptacle 65 which is suspended from the hook 64. It should be noted that this coin receptacle is provided with a lining 65' 95 to prevent noise when the coin drops into the receptacle and that it is further provided with a lip 66 serving to prevent danger of the coin missing the receptacle.

The operation of this coin control vending machine is as follows:—The vending machine is mounted in a suitable place and may be of such size that it may be conveniently connected with the back of a theater chair. One advantage in having the device circular in shape is that it will not readily catch upon clothing and tear the clothing. The coin is placed in the slot 67 and passes between the jaws 51 and 57, the jaw 51 having of course been adjusted to the proper position. This coin moves the movable jaw 57 and with it the latching pawl 59 thus swinging the latching pawl out of the operative position for engagement with the abutment 40. The handle 26 is then moved upwardly to the dotted line position shown in Fig. 1 and the pawl 41 by engagement with the abutment rib 40 will rotate the band 38 thus bringing the article to be dispensed into position for passing through the openings 22 and 25 which will now be in alignment. As the closure rotates, the lug 63 will strike the coin thus moving the same from between the jaws 51 and 57, releasing the jaws and permitting the jaw 57 and latch 59 to return to their operative position. The coin will drop 110 into the coin box where it will be held until the coin box is removed. Upon releasing the handle 26, this handle will act as a weight to return the closure to the position 115 shown in Fig. 3, the pawl 41 riding over the 120 125 130

abutment rib and the rib moving past the free end of latch 59. The machine will then be held against movement until a new coin is inserted. After the merchandise have all 5 been dispensed, the rib 68 which is provided with a hook will be in position for engagement with the hook 69 of the pawl 59 thus preventing the pawl from moving to the inoperative position if it is attempted to place 10 a coin in the machine. Therefore it is impossible to place a coin in an empty machine.

When refilling this machine, the key will be inserted in the key-hole 70 and turned to release the lock. The cover or closure can 15 then be removed and new articles placed in the compartments formed by the partition.

39. At the same time the coin receptacle 65 can be removed from the hook 64 and after the coins have been emptied, the receptacle 20 can be put back in place.

I have thus provided a coin control vending machine which will be so constructed that a coin cannot be inserted when the machine is empty and which is further so constructed 25 that a coin of a smaller denomination than intended for the machine cannot be used.

I have further provided a machine which is so constructed that the coin control mechanism may be adjusted for the size of coins 30 to be used thus permitting the machine to be used with various priced merchandise.

I have further provided a machine which is so constructed that the same will take up a 35 comparatively small amount of space while at the same time permit a relatively large amount of merchandise to be dispensed.

I have further provided a machine which will be rather simple in construction but at 40 the same time very effective in operation and not liable to easily get out of order or need repair.

What is claimed is:

1. A dispensing machine comprising a 45 housing provided with an outlet, a closure rotatably mounted upon said housing and provided with an outlet registering with the outlet of the housing when the closure is moved to an adjusted position, a container 50 rotatably mounted in said housing, means for releasably holding said container against rotary movement in said housing, and means carried by said closure for moving said container in said housing when said closure is 55 moved to bring its outlet into registry with the outlet of said housing.

2. A vending machine comprising a housing 60 provided with an outlet, a closure rotatably mounted upon said housing and provided with an outlet for registering with the outlet of the housing when the closure is moved to an adjusted position, a band 65 rotatably mounted in said housing and provided with arms forming partitions, means carried by said housing to releasably

hold said band against rotation in said housing, and means carried by said closure for rotating the band within the housing when the closure is moved to bring its outlet into registry with the outlet of said housing.

3. A vending machine comprising a housing, a closure rotatably connected with said housing and provided with an outlet moving to an operative position when said closure is rotated to an adjusted position, a container 70 movably mounted in said housing, means carried by said closure for engaging said container to move the same to an adjusted position with said closure, and means for releasably preventing movement of said container.

4. A dispensing machine including a housing having an outlet, a container movably mounted in said housing, a closure movably connected with said housing and having engagement with said container for moving the same to an adjusted position with said closure, and means for releasably preventing movement of said container.

5. A dispensing machine including a housing, a container rotatably mounted in said housing, a closure having engagement with said container for moving the same to an adjusted position with said closure, and means for releasably preventing movement 90 of said container, said means including a stationary jaw, a movable jaw, and a pawl forming an extension from said movable jaw, said pawl being swung to an inoperative position by said movable jaw when a 95 coin is placed between the jaws.

6. A dispensing machine including a housing, a container rotatably mounted in said housing, a closure rotatably connected with said housing, means carried by said closure 105 for engagement with said container to move the same to an adjusted position when said closure is moved in one direction, a stationary jaw positioned in said housing, a movable jaw positioned in said housing adjacent said stationary jaw and provided with an extension forming a pawl to engage said container and releasably prevent movement thereof, said movable jaw being moved to an adjusted position by coins between the 110 jaws, and said closure being provided with means for removing the coin from between the jaws when the closure is moved to rotate said container.

7. A dispensing machine comprising a 120 housing, a closure for said housing movably connected therewith, a band rotatably mounted in said housing and provided with arms forming partitions, means for releasably preventing movement of said band including a stationary jaw, a movable jaw positioned adjacent said stationary jaw and provided with an extension forming a locking pawl for engaging the band to releasably prevent movement thereof, said pawl 125 130

being swung to an inoperative position by a coin placed between the jaws, means carried by said closure for moving the band within the housing when the closure is moved in one direction, and means carried by the closure for removing the coin from between said jaws.

8. A dispensing machine including a housing, a closure for said housing, a container movably mounted in said housing and moved in one direction by said closure, coin control means for releasably holding said container against movement in one direction and moved to an inoperative position by a coin, and means carried by said closure for removing the coin from the coin control means to permit the same to return to an operative position and lock said container against movement.

20 9. A dispensing machine including a housing, a container movably mounted in said housing, a closure provided with means for actuating said container to move the same to an adjusted position, a bracket 25 mounted in said housing, a jaw adjustably connected with said bracket, a movable jaw connected with said bracket in operative relation to the adjustable jaw, and provided with a pawl for engaging said container to releasably hold the same in a stationary position, said movable jaw swinging said pawl to an inoperative position when a coin is placed between the jaws, and means for moving a coin from between the jaws when 30 the closure is swung to move said container to an adjusted position.

10. A dispensing machine including a housing, a closure rotatably connected with said housing, a lock carried by said closure, 40 means carried by said housing for engagement by said lock to releasably hold the same in place and permit rotary movement of the same when in place, a container mov-

ably mounted in said housing and moving to an adjusted position when said closure is 45 rotated in one direction, and coin control means normally preventing rotary movement of said container.

11. A dispensing machine including a housing, an arm extending from said housing and provided with a flange at its free end portion, a closure rotatably mounted upon said housing, a lock carried by said closure for engaging the flange to prevent removal of said closure and permit rotary 50 movement of the closure when in place, a container movably mounted in said housing, means for moving said container with said closure when the closure is moved in one direction, coin control means for releasably 55 preventing movement of said container, and means carried by said closure for removing a coin from the coin control means to permit the same to return to an operative position. 65

12. A vending machine including a housing, dispensing means in said housing movable therein, a closure operating said dispensing means, and coin control means releasably preventing movement of said dispensing means, said coin control means including a support, a movable jaw connected with said support and provided with an extension forming a pawl for engaging the dispensing means, an adjustable jaw connected with said support, a plate connected with said support between said jaws, and a pin adjustably connected with said plate between the jaws. 70 75

In testimony whereof I affix my signature 80
in presence of two witnesses.

JOSEPH T. SHELHORN.
